Google's giant kite by Dacia J. Ferris, posted Dec. 6, 2018, found online [Mar. 25, 2019] <https://www.teslarati.com/google-x-clean-energy-kite-wind-power-generation-anywhere/>.*

Primary Examiner — Marissa J Cash(74) *Attorney, Agent, or Firm* — McDonnell Boehnen Hulbert & Berghoff LLP(57) **CLAIM**

The ornamental design for an energy kite wing, as shown and described.

DESCRIPTION

FIG. 1 is a perspective view of an energy kite wing;

FIG. 2 is a further perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

In the drawings, broken lines immediately adjacent shaded surfaces represent boundaries of the claim and form no part thereof; all other broken lines depict environmental subject matter that forms no part of the claim.

1 Claim, 8 Drawing Sheets(56)
